CLAIM

The ornamental design for a splash guarded elevating bathing tub, substantially as shown.

DESCRIPTION

FIG. 1 is a perspective view of the splash guarded elevating bathing tub of this invention in the elevated position taken from a front corner.

FIG. 2 is a perspective view of the tub of FIG. 1 taken from the back corner diagonally opposite to that of FIG. 1.

FIG. 3 is a front elevation view of the tub of FIG. 1.

FIG. 4 is plan view of the tub of FIG. 1; and,

FIG. 5 is a side elevation view of the tub of FIG. 1.

The broken line showing an elevating unit is included for the purpose of illustrating a portion of the bathing tub that forms no part of the claimed design.
